CARTON

S Bernard Joffee, Kansas City, Mo.

Application December 14, 1936, Serial No. 115,763

1 Claim. (Cl. 229—15)

This invention relates to cartons of the nature employed in holding commodities in attractive conditions to be sold to the retail trade and the primary object of the invention is the provision of such a carton wherein is employed a number of compartments each marked to represent the days of the month and having associated therewith and in the carton a header upon which may be printed or otherwise marked, the name of the particular year, month and day.

Another important aim of the instant invention is the provision of a novel and unique carton of the aforementioned character which may assume the nature of a box within which is packed such widely sold articles as candy, nuts, fruits and the like, and to fulfill the concepts of the invention, the said articles should be isolated in compartments appropriately marked so that the user will have some guide as to the number of articles he is to consume each day of the calendar month, said box being so constructed as to at once reveal to the user the number of commodity units he has consumed and also the date and whether or not the commodity unit for any particular day has been consumed.

It is well known in the candy or confectionery trade that over-indulgence oftentimes is an element which precludes purchasers from buying larger quantities of candy and it has been felt that if some means could be employed whereby the consumer could govern the amount of candy consumed per day or per week, that the sales of such confections would rise.

To fulfill the aforesaid apparent desire on the part of the candy dealers therefore, a carton simulating a calendar and especially the calendar for any particular month has been designed to embody the invention. Investigation has also revealed that commodities other than candy might be sold to advantage through the employment of such cartons and therefore the preferred embodiment of the invention which is illustrated in the accompanying drawing is merely one exemplification of the broader points of the invention.

45 In the drawing,

Figure 1 is a perspective view of a carton made to embody the present invention.

Fig. 2 is a cross sectional view through the same taken on line II—II of Fig. 1.

50 Fig. 3 is a partition blank showing the same in condition before insertion into the carton, and

Fig. 4 is a blank of another partition.

In constructing the especially formed carton the same should be provided with a tray-like receptacle having a bottom 6 and upstanding sides

8 that will form the lower half of a telescoping box of well known type. A header 10 formed of material the same as that from which the tray-like receptacle is created occupies a small portion of the receptacle and preferably extends across one side thereof so as to present a panel 12 upon the face of which may be imprinted the year as at 14, the month as at 16 and the days of the week as at 18. This header 10 is U-shaped in cross-section and the down-turned legs 20 of their lower edges resting upon bottom 6 and the face of panel 12 in a plane substantially the same as the plane of the upper edges of sides 8. The reason for constructing header 10 as mentioned is to permit the manufacturer to print a year's supply, for example, of headers and insert them into the tray-like receptacles as the trade demands. If the retailer has a number of "December" boxes of candy at the close of said month, then header 10 may be bodily removed, destroyed, and a header for the subsequent month positioned in its stead.

The major portion of the tray-like receptacle is subdivided into a plurality of compartments through the employment of partitions 22 and 24. Partitions 22 are formed to extend across the receptacle in planes parallel to one leg 20 of header 10 and in blank, appear as Figure 3 indicates. Each partition 22 has a series of notches 26 formed inwardly from one edge thereof and at 30 spaced apart points so as to provide a number of stretches 28. In some instances partition 22 will have a tab 30 extending outwardly from the aforesaid edge thereof in each stretch 28. In the example illustrated partition 22 is the one which is directly against header 10 and therefore, the date tabs 30 are not needed for each receptacle. Other months obviously will require that there be a tab 30 extending outwardly from each stretch 28. Separately forming partitions 22 so that partitions 24 will interlock therewith permits the printing of these dated partitions so that assembly becomes easy and no time is lost in preparing boxes for any particular month of the year. Only the partition 22 adjacent to header 10 and partition 22 parallel to and next adjacent the upstanding side opposite to header 10 need be changed. Each partition 24 is provided with a series of inwardly extending notches 32 which when interlocked with the notches 26 of partitions 22 will create a grill work of partitions which presents the plurality of compartments in a conventional manner. After partitions have been moved to place and the commodity, such as pieces of candy 34, positioned in the numbered 55

compartments, tabs 30 are hinged down along the line 36 so as to overlie the compartment and candy 34 therein. After the carton has been so constructed and filled the standard type of cover 5 may be telescoped to place and the package is ready for sale.

In the carton illustrated in Figure 1, pieces of candy for the 1st, 2nd, 3rd, 4th and 5th of December, 1936 have been consumed and if the user 10 has been accurate in consuming the first five pieces of candy, the date to follow is the 6th and there remains a piece of candy to be consumed on that date.

Practice has taught that a carton of this particular character is extremely useful in merchandising a large number of commodities and the invention might be included in commodity carriers having different physical characteristics than that illustrated herewith.

20 What I claim as new and desire to be secured by Letters Patent is:

A carton of the character and for the purpose specified comprising a tray-like receptacle having a bottom and upstanding sides; a header along one side of the receptacle, occupying a minor portion thereof; a number of intersecting 5 partitions disposed in the remaining portion of the receptacle to sub-divide the same into a plurality of commodity-receiving compartments; and indicia-receiving tabs integral with certain of the partitions each overhanging a compartment re- 10 spectively, said header and upper edges of the partitions being in substantially the same plane as the upper edges of the upstanding sides of the tray-like receptacle, said tabs being extended laterally to one side of the partitions and having 15 elements thereon forming dates of a calendar month, there being a tab and an associated compartment for each day of any certain month of the year.
